Inventor
By his Attorney
Petherston & Co.

UNITED STATES PATENT OFFICE.

AUGUST W. OFELDT, OF WEST HOBOKEN, NEW JERSEY.

SPARK PLUG.

Application filed October 24, 1921. Serial No. 510,120.

To all whom it may concern:

Be it known that I, AUGUST W. OFELDT, a citizen of the United States, residing at West Hoboken, in the county of Hudson 5 and State of New Jersey, have invented certain new and useful Improvements in Spark Plugs, of which the following is a clear and exact specification, reference being had to the drawings which form a part of 10 the specification.

This invention relates to spark plugs and my improvement is directed to a plug structure wherein means are provided for establishing a highly heated zone in the vicinity 15 of the electrodes to ensure combustion of the oil and fuel which would otherwise tend to collect in that region and form carbonaceous deposits, with the deleterious effect of short circuiting the flow of current.

20 The provision of a pocket or chamber in a plug behind the spark gap is well known to the art, and the expansion which occurs therein is useful in that oil and residual fuel are discharged, and the electrodes 25 cleaned thereby; but this action is most efficient when the engine is running at high speed or under heavy loads.

When the engine is starting up or while idling, with the jacket water keeping the 30 temperature down, the walls of the plug chamber may not become sufficiently hot to permit complete combustion of the oil and fuel, because the heat of combustion is too quickly absorbed by the cooling system, 35 and it is at such times that carbonization occurs. It is therefore one of the purposes of my invention to provide means for preserving the heat of combustion in the spark plug chamber under all conditions of motor 40 operation, so that complete combustion may occur therein, thus preventing the formation of carbon deposits.

This result is accomplished through my invention by the provision of an extremely 45 thin cylindrical wall for the interior of the plug chamber, and surrounding this wall with an air space to serve as an efficient heat insulation, so that the wall will be capable of quickly absorbing the heat of the 50 explosions, and, by reason of the external insulation, this heat will be concentrated within the chamber to establish the desired hot zone therein.

Other features and advantages of my in- 55 vention will hereinafter appear.

In the drawing:

Figure 1 is a sectional elevation of my improved spark plug, as applied.

Fig. 2 is a detail of the flanged sleeve which coacts with the inner surface of the 60 shell to constitute an insulating air space.

Fig. 3 is a detail of the packing ring.

Fig. 4 is a detail of the cap electrode, and

Fig. 5 is a detail of the securing ring.

In the drawings, let 1 indicate the porcelain in which is axially fitted the central electrode 2, the porcelain having the usual shouldered portion 3, which engages within the threaded shell 4, these parts being of well known character.

A packing ring 5 lies between the porcelain and shell 4, and is pressed against the shoulder 3 of the porcelain by a sleeve 6, which is provided with the external flanges 7, 8, that are located respectively at its opposite ends.

There is thus provided an annular air space 9 between the sleeve 6 and the inner surface of shell 4, this space being bounded at its ends by the flanges 7 and 8.

The other electrode 10 is in the form of a concavo-convex cap, with a central orifice 11 to present its edge in spark-gap relation with electrode 2. The cap 10 has a radial flange 12 whereby it lies against the outward flange 8 of sleeve 6, and the parts are secured within the shell by a threaded ring 13 which is screwed into the forward end of the shell and bears against the flange 12.

It should be noted that the wall of sleeve 6, between the flanges 7, 8 is of extremely thin material, in order that it may have the quality of rapid heat absorption; also that the space 9, being an air space, serves as a highly efficient insulator to prevent loss of heat by radiation from the plug chamber.

Similarly the cap electrode 10 is of thin material in order that it too may possess the quality of rapid heat absorption, to aid in maintaining a high temperature within the 100 plug chamber.

By these means the oil which enters the plug chamber is either consumed therein or is held in such fluid state as to prevent the formation therefrom of carbonaceous deposits upon and about the porcelain or other insulation member, and also the fuel mixture which enters the plug chamber becomes either entirely consumed or its residue held in such free state that it, together with any 110

unconsumed oil, will be discharged from the plug chamber by the force of the explosions which occur therein.

Variations within the spirit and scope of 5 my invention are equally comprehended by the foregoing disclosure.

I claim:

1. A spark plug comprising a shell, an insulation member therein having a recess in 10 its forward portion, a central electrode carried by the insulation member and extending out through the recess, an apertured cap electrode in spark gap relation with the central electrode, and a sleeve disposed concentrically between the recessed portion of 15 the insulation member and the shell, the sleeve having external end flanges which coact with the shell in the provision of an annular air space, to prevent heat radiation and thereby maintain a high temperature within and 20 about the insulation member.

2. A spark plug comprising a shell, an insulation member therein having a recess in its forward portion, a central electrode carried by the insulation member and extending 25 out through the recess, an apertured cap electrode in spark gap relation with the central electrode and having a radial flange, a sleeve disposed concentrically between the recessed portion of the insulation member 30 and the shell, the sleeve having external end flanges which coact with the shell in the provision of an annular air space, to prevent heat radiation and thereby maintain a high temperature in and about the insulation 35 member, and a ring to fit within the shell end, clamping the cap flange against the outer flange of the sleeve.

Signed at New York, in the county and State of New York, this 20th day of October, 40 1921.

AUGUST W. OFELDT. [L.S.]
